UNITED STATES PATENT OFFICE

1,989,949

ELECTRICAL CONNECTER PLUG

John E. Smith, Belleville, Ill., assignor to Knapp-Monarch Company, Belleville, Ill., a corporation of Missouri

Original application September 29, 1930, Serial No. 484,950. Divided and this application November 21, 1932, Serial No. 643,620

2 Claims. (Cl. 177—311)

My invention relates to an electrical connector plug and is shown as more particularly applied to that type of plug intended to be detachably connected to electrical appliances.

5 My present application is a division of my co-pending application Serial No. 484,950 for Electrical connector plugs, filed September 29, 1930.

It is a further object of my invention to provide a resistor in the form of a coiled guard for 10 the current supply wires, said resistor being in circuit with an electric appliance and an indicator lamp being connected across said resistor.

Other and further objects of my invention will 15 be apparent from the following specification taken in conjunction with the accompanying drawing, wherein:

Figure 1 is a front elevation of my improved connector plug.

Figure 2 is a rear elevation of the same.

20 Figure 3 is a side elevation of the plug.

Figure 4 is a front elevation of the plug with the top half thereof removed; and

Figure 5 is a diagram showing the circuit connections to and in my improved connector plug.

25 My invention contemplates an indicator lamp connected in a shunt circuit through the appliance so that if the lamp should burn out, the appliance can be used without the lamp having to be replaced.

30 In order to protect the lamp from damage by being in an exposed position, I arrange the lamp within the body of the connector plug. However, it is not practical to use a 110 volt lamp in the connector plug, even if it were practical to get a lamp of such a voltage in the confined area of 35 the body of the plug, for the reason that the heat of the lamp would be so great it would affect the material of which the plug is composed and perhaps cause other damage to the connections, as well as rendering the plug uncomfortably hot to 40 handle.

Therefore, I propose to use an ordinary flash light bulb requiring but 2 to 3 volts and drawing but 200 milliamperes of current. Such a low 45 wattage lamp will generate practically no heat and certainly none of a serious character within the confined space permitted on the interior of a connector plug.

I am enabled to use such a low voltage lamp by 50 connecting the same about a resistor so as to take the drop thereacross, the resistor being in series circuit with the circuit through said appliance. However, it is important that the resistor shall not be confined within the body of 55 the plug for it is apparent that the energy con-

sument therein would be dissipated in heat and that heat liberated within the body of the plug would be as undesirable as if a 110 volt lamp were used.

Accordingly, I propose to arrange the resistor 5 wire outside the plug. My arrangement substitutes the resistor for the coiled spring guard usually found on connection plugs where the connector cord enters the plug.

Inasmuch as the indicator lamp may burn out 10 and therefore need replacement, I provide an opening in one half of my improved connector plug through which the concealed lamp may be removed and a fresh lamp inserted and over the opening I provide an apertured guard. 15

Referring to the drawing, my improved plug is formed of two pieces, an upper half 11 and a lower half 12. All of the electrical connections in the plug are located in the lower half of the plug, the connecting strips, etc., being embedded 20 in appropriate grooves or channels. Wherever it is necessary, the upper half 11 has complementary grooves or channels cooperating with those of the lower half to properly enclose the plug and its connections. As this is the usual 25 practice in this art, it is only believed necessary to describe in detail the lower half of the plug, shown in Fig. 4.

At the reduced end 13 of the plug, there are located two channels 14 and 15 terminating in 30 openings at the end of the plug. In these channels are embedded spring clips 16 and 17, respectively. These clips may be of any of the usual and well known constructions adapted to engage the projecting pins 16a and 17a ordinarily 35 constituting the terminals of the heating element E of an electric appliance (see Figure 5).

However, the clip 17 is provided with an extension 18, the purpose of which will be more fully 40 hereinafter set forth.

The channels 14 and 15 are of a considerable depth to accommodate the clips 16 and 17, but the flat terminal portion 19 of each clip rests in a groove that is only deep enough to accommodate it.

A pair of metal strips 21 and 22 join respectively with the terminals 19 of the spring clips 16 and 17, screws 23 serving to hold the strips and the terminals in electrical engagement with each other. The screws engage in screw-threaded bushings, not shown, which bushings are embedded in the insulating material of which the plug is composed. The connecting strips 21 and 22 rest in appropriate channels or grooves of a 50 shape and size to accommodate the strips which 55

5 terminate respectively at terminal screws 24 and 36. It will be noted that the strips 21 and 22 extend longitudinally of the plug adjacent the opposite side edges thereof. Between the channels for these strips is located an enlarged cut-out portion or pocket 26 adapted to house an indicator lamp 27.

10 The indicator lamp 27 comprises a bulb 28, which is shown as rounded, housing a filament 29. Such lamps are ordinarily provided with a screw-threaded metallic shell 31 on the base portion constituting one of the terminals of the filament 29. A terminal 32 on the end of the base constitutes the other terminal for the filament 29, the two terminals 31 and 32 being insulated 15 from each other.

15 The base of the lamp 27 is received in a substantially semi-circular or U-shaped spring clip 33 (see Figure 4) which has a metallic strip 34 secured thereto. It will be noted that the strip 34 passes under the connecting strip 22 and at a third terminal screw 36 that is located at the center of the plug.

20 It will be noted that the connecting strips 21 and 34 bend downwardly, while the connecting strip 22 bends upwardly in Figure 4 in order to properly space the terminal screws 24, 36 and 25 from each other.

25 I propose to use an ordinary two wire connector cord, the wires of which are indicated at 41 and 44. The conductors 41 and 44 are connected respectively to the terminal screws 24 and 25, thus establishing electrical connection with the connecting strip 21 and the spring clip 16.

30 I have arranged a resistor 63 in the form of a coil and disposed at the same place where the connector cord enters the connector plug, the coil resistor 63 thus taking the place of a coiled spring guard. The resistor 63, of course, is insulated as illustrated so as to prevent any possibility 35 of it shocking or burning the user while energized.

35 The lowermost turn of the resistor 63 is of a diameter to fit into an annular groove 64 while the coil itself extends through a bore 42 of the plug. At the upper end of the coil, I provide an insulated ring 65 protecting the upper coil of the guard, as is the usual practice.

40 One end of the resistor 63 is connected to the terminal screw 36, the other end extending down through the coil alongside the connector cord and terminating beneath the terminal screw 25.

45 The resistance wire 63 is chosen to have a predetermined ohmic resistance, the IR drop across which corresponds to the voltage required to properly energize the lamp 27. I have found that the flash light lamp requires but 2.2 volts to operate it. The wire 44 being connected with the terminal screw 25, supplies current to the strips 22 and 19 and to the projection 18.

50 Communicating with the pocket 26 is a cylindrical bore 51 which is made of a size and length sufficient to receive a coiled spring 52. One end of the spring 52 is closed by a plate 53 against which the terminal 32 of the lamp rests when the lamp is in place. Thus the electrical connection is made from the terminal 19 of the clip 17 through the arm 18, spring 52 and plate 53 to the terminal 32 of the lamp. This is the connection which is designated generally by the reference numeral 48 in the circuit diagram of Figure 5.

55 A projection 55, at the opposite end of the pocket 26, is formed of the material of which the plug is composed and extends into the pocket 26 so as to engage the end of the bulb 28. As the

5 lamp 27 is inserted in place in the plug, it must be pressed home between the projection 55 and the plate 53 and this is sufficient to slightly compress the coiled spring 52. The lamp 27 is then held firmly from movement longitudinally of the plug by this arrangement and it is held from movement sidewise of the plug by the semi-circular spring clip 33.

10 The two halves of the plug 11 and 12 are held together by two or more screw bolts indicated at 57, these passing through appropriate holes 58, extending through the halves of the plug and located in the parts that are thickest, that is to say, where there are no grooves or cutaway portions. When the two halves of the plug are assembled 15 in this manner, the coiled resistor 63 is retained in position relative to the plug by the portion of the resistor mounted in the semi-cylindrical groove 64 of each half of the plug.

20 In order that the lamp may be removed from the plug without removing the bolts 57, I make the opening 61a in the front of the plug sufficiently large and circular to permit the passage of the lamp 27 therethrough. Over this opening I provide a grille or guard 64a which is riveted 25 to the outside of the upper half 11 of the plug, as indicated at 65a. The riveting is intended to hold the grille or guard 64a in frictional engagement with the surface of the plug 11 so that it may be pushed aside, pivoting on the rivet to permit the lamp to pass through the opening 61a.

25 A stop 66 is provided on the plug along one edge of the guard 64a so as to limit its movement in one direction.

30 When it is desired to replace the lamp 27 in the plug, any instrumentality, such as a match, may be inserted in the rear aperture 62 to press the bulb 28 upwardly and out through the opening 61a after the grille 64a has been moved out of the way. Here, a person taking hold of the bulb 35 28 with his fingers can readily extract the same from the plug. A fresh lamp is reinserted through the opening 61 so that the base thereof engages in the clip 33, whereupon a simple pressure upon the lamp 27 with the finger will force the lamp 40 45 home, the rounded surface of the bulb 28 serving as a cam on the abutment 55 to push the lamp 27 longitudinally in the clip 33 and to cause engagement of the terminal 32 on the lamp with the plate 53. After the lamp is inserted in place, the 50 grille 64a is returned over the opening 61.

55 Some changes may be made in the construction and arrangement of the parts of my device without departing from the real spirit and purpose of my invention, and it is my intention to 55 cover by my claims, any modified forms of structure or use of mechanical equivalents, which may be reasonably included within their scope.

I claim as my invention:

1. In combination, an electrical connector plug 60 adapted to connect an appliance which has an electrical element therein in circuit with a current supply outlet, said plug comprising a pair of contact members having circuit connections thereto, a two-wire connector cord extending between 65 said outlet and plug and a coiled wire guard about the connector cord where it enters the connector plug, said guard being formed of insulation covered electrical resistor wire, the opposite ends of which are connected with one of said contact 70 members and with one end of the electrical element of said appliance; an indicator lamp and means for mounting said indicator lamp on said plug in shunt circuit with said resistor wire.

2. An electrical connector plug comprising a 75

body portion, a signal device carried thereby, a pair of prong receiving sockets at one end of said body portion, a coiled wire guard at the other end thereof and a two wire connector cord extending through said coiled wire guard, said

5
cal resistor wire, the opposite ends of which are connected in series circuit between one of the connector cord wires and one of said prong receiving sockets and means for connecting said signal device in parallel with said resistor wire. 5

JOHN E. SMITH.
